MOUNTING FOR MEASURING INSTRUMENTS

Filed Dec. 8, 1930

Inventor

Joseph B. Meriam

By

Arthur H. Van Horne

his attorney

UNITED STATES PATENT OFFICE

JOSEPH B. MERIAM, OF CLEVELAND, OHIO

MOUNTING FOR MEASURING INSTRUMENTS

Application filed December 8, 1930. Serial No. 500,751.

My invention is an improvement in measuring instruments and relates more particularly to mountings therefor.

One of the objects of my invention is to mount measuring instruments such as manometers or the like so that they may be partly dismantled for cleaning without disturbing external connections.

Another object of my invention is to provide a simple separable mounting of the type described which is inexpensive to manufacture and which affords a protective housing for the instrument.

Other objects and advantages of my invention will become more apparent from the following description of an embodiment thereof reference being made to the accompanying drawing in which like reference characters are employed to designate like parts throughout the same.

Figure 1 is a front elevation of an embodiment of my invention.

Figure 2 is a side fragmentary elevation thereof.

Figure 3 is a vertical section partly in elevation taken on line 3—3 of Figure 2.

Figure 4 is a bottom plan view of the upper separable section of the mounting.

In carrying out my invention one embodiment of which is illustrated in the accompanying drawing I provide a mounting or housing for measuring instruments such as manometers or the like, in which the housing is formed of separable sections which when assembled together permit the communication of fluids therebetween.

In the embodiment illustrated, I have shown the usual manometer U-tube 1 removably secured within one of the separable housing members 2. The upper ends 3 of the arms of the tube extend through openings 4 in the housing, while the bend of the tube may be anchored to the housing back wall by means of a clip or wire 5 passing through openings 45 in the wall and secured behind the wall. A

packing 6 of cork or the like is interposed between the tube and the back wall of the separable section 2 to provide a cushion seat for this portion of the tube. A scale 7 is slidably adjustable along the tube and is carried by the separable section of the mounting 2.

Section 2 of the mounting is preferably cast in one piece and comprises a back wall 8 and outwardly extending side and bottom peripheral walls 9 and 10 respectively. These walls constitute a protective housing for the glass tube of the manometer and extend outwardly to intersect a plane beyond the tube walls. This casting is also provided with a head portion 11 which is provided with a central threaded opening 12 for receiving a pin 13.

The mounting also includes a cooperating separable section or head 14 which is provided with a central opening 15 for receiving the pin 13.

It will be noted that the upper ends of the tube arms 3 extend beyond the casting 2 and into cooperating openings 16 formed in the head 14. Conduits 17 forming a part of a fluid circuit in which the manometer is connected may be permanently threaded into openings in the head 14 as shown in Figure 3. These conduits communicate with the openings 16 and with the manometer tube by means of the ducts 18.

I have provided suitable packing means between the head 14 and the separable mounting section 2, as indicated at 19. In order that the separable sections of the mounting may be secured together in fluid transmitting relation I have provided a wing nut or other fastening means 20 on the pin 13. It will therefore be seen that by screwing the nut 20 downwardly on the pin the separable sections of the mounting may be brought together in fluid transmitting relation without danger of leakage.

In order to properly seat and position the head 13 on the section 2 I have provided guide pins 21 which may be carried by the

head 11 and which extend into corresponding openings in the head 14.

When it is desired to clean the manometer tube 1, or, in the event of damage to the tube, it is desired to replace it with another tube it is not necessary to disconnect the mounting as a unit from the fluid system in which the manometer is a part. By my invention I have provided a separable mounting which permits the cleaning or replacement of a tube by simply removing the nut 20 and drawing the separable section 2 downwardly from the head 14 without disconnecting the conduits 17 from the head. In this manner considerable time may be saved in cleaning or repairing a measuring instrument provided with a mounting constructed in accordance with my invention.

Various changes may be made in the details of construction and arrangement of parts without departing from the spirit of my invention or the scope of the appended claims.

I claim:

1. In a manometer, a manometer tube, a mounting for the tube including a head having means adapted for connection with a fluid pressure line, and a housing for the tube separably connected with the head and having openings through which the ends of the tube protrude, said openings affording communication through the head for the tube ends with the fluid pressure line.

2. In a manometer, a manometer tube, a mounting for the tube including a head having means adapted for connection with a fluid line, a housing for the tube separably connected with the head and having openings through which the ends of the tube protrude, said openings affording communication through the head for the tube ends with the fluid line, and means for guiding said head and said protruding tube ends into fluid transmitting relation when the head and housing are moved into position to be secured together.

3. A mounting for manometers including a head, a manometer tube support separably secured to the head, said head having openings therethrough for connection at one of their ends with a fluid line and at their other respective ends with a manometer tube, a manometer tube carried by the support, packing means between the head and the support, a pin carried by the support and extending through the head, and means cooperating with the pin to separably secure the head and support together.

4. A manometer mounting comprising separable body and head portions having communicating openings therein to receive the ends of a manometer tube, said head portion having means adapted to be connected to a source of fluid, and means carried by the body

portion for detachably securing the head and body portions together.

5. A manometer comprising a manometer tube, a housing for the tube having openings therein to receive the ends of the tube, said housing including a separable head having openings therein adapted for connection to a source of fluid and to the ends of said manometer tube, and means for detachably securing the head in place.

In testimony whereof, I hereunto affix my signature.

JOSEPH B. MERIAM.
